United States Patent Office.

DAVID CARROLL, OF UNION, PENNSYLVANIA.

Letters Patent No. 64,628, dated May 14, 1867.

IMPROVEMENT IN STUMP EXTRACTOR.

The Schedule referred to in these Letters Patent and making part of the same.

TO ALL WHOM IT MAY CONCERN:

Be it known that I, DAVID CARROLL, of Union, in the county of Erie, and State of Pennsylvania, have invented a new and improved Stump Extractor; and I do hereby declare that the following is a full, clear, and exact description thereof, which will enable those skilled in the art to make and use the same, reference being had to the accompanying drawings, forming part of this specification.

My invention relates to that class of machines employed for extracting stumps in fields, and consists in the employment of an endless chain, in combination with three wheels, over and around which the chain works, the said wheels being located upon a derrick erected for the purpose. In the accompanying drawings—

Figure 1 is a plan view of my improved stump extractor.

Figure 2 is a side elevation of the same.

Letters of like name and kind refer to like parts in each of the figures.

I erect a derrick, composed of three inclined posts B B B, with the upper ends firmly bolted or secured to a cross-timber, C. Immediately below the cross-timber C is another strong cross-timber, D, firmly secured to two of the posts B. Between the two cross-timbers C and D is located a pulley, E, constructed in such a manner as to fit the links of a chain, for the purpose of operating the same. This pulley D is rigidly secured to the vertical shaft F, that is provided with journals which run in suitable bearings secured to the cross-timbers C and D. G is also a pulley, constructed in the same manner as the pulley E, secured to the horizontal shaft H, that has bearings in two of the posts B B. I is another pulley, made the same as the pulleys E and G, so that its surface will admit the links of a chain, and assist in operating it. The pulley I is secured to a short shaft, that has bearings, and runs in a bifurcated bar or straps J, the shank end of which is pivoted around the shaft H, so that the pulley I may be elevated or lowered, or will move in the arc of a circle described by the shank or strap J upon the shaft H. At the side of the pulley G is secured a gear-wheel, K, that meshes and works in a corresponding gear-wheel, L, that is secured to the side of the pulley I. M is an endless chain that works over the pulleys before described. In the loop of the endless chain M is attached a single chain, N, employed for the purpose of hitching around the roots of a stump, as shown at O, fig. 1, for the purpose of extracting it from the ground. P is a cross-bar, located and secured across the top of the vertical shaft F. At each end of the bar P is attached by joints *i i* a bifurcated lever, Q, by which the machine is operated. At the lower ends of the inclined posts B are caster-wheels and shoes R R R, secured for the purpose of moving the machine from one place to another, and to prevent the posts from sinking into the ground when the machine is in operation. *e e e* are timbers, running horizontally around the derrick, and firmly secured to the posts, for the purpose of adding strength and stability to the derrick.

When it is desired to operate the machine, it is placed over the stump in such a position as to bring the single chain N perpendicular over the point where it is designed to be hitched. Power is then applied to the end of the lever Q, and moved around in the direction of the arrow *a*, which causes the endless chain M to move in the direction of the arrows *e e*, which brings the single chain N to act directly upon the stump, and raise it from the ground.

Having thus described my invention, what I claim as new, and desire to secure by Letters Patent, is—

1. The pulleys E, G, and I, in combination with the chains M and N, substantially as shown and described, and for the purposes set forth.
2. I claim the casters and shoes R R R, in combination with the derrick, substantially as shown and described, and for the purposes set forth.

DAVID CARROLL.
